UNITED STATES PATENT OFFICE.

FERDINAND WALTERS, OF COVINGTON, KENTUCKY, ASSIGNOR TO C. F. WALTERS AND S. H. STOUT, JR., OF SAME PLACE.

MILL-DRIVER.

Specification of Letters Patent No. 24,268, dated May 31, 1859.

To all whom it may concern:

Be it known that I, FERDINAND WALTERS, of Covington, in the county of Kenton and State of Kentucky, have invented a new and 5 useful Improvement in Millstone-Drivers; and I do hereby declare that the following is a full, clear, and exact description thereof, reference being had to the accompanying drawings, and to the letters of reference 10 marked thereon and made to form a part of this specification.

The nature of my invention relates to the construction and arrangement of a divided adjustable mill stone driver, as hereinafter 15 set forth and described.

In reference to the accompanying drawings, Figure 1, is a perspective view, showing the driver arranged as for use. Fig 2, is a horizontal sectional view showing the 20 peculiar construction and arrangement of the driver.

(A) represents an upper, and (B) a lower mill stone for grinding purposes.

(C) is the driving shaft, provided with 25 strong supporting cap (e).

(d, d') represents the divided adjustable driver pivoted to the cap (e) at (e) in such manner, that its ends and center are allowed a certain degree of lateral motion, the center 30 of the driver (d, d') is made to fit loosely around the shaft (C) so that its lateral working may not be impeded by the shaft.

(g) is an ordinary balance rynd, made to rest upon the top of the shaft (C) as shown in Fig. 1, and fitted to the driver as shown 35 fully in Fig. 2.

It will be readily seen that the driving power applied to the running stone (A) must necessarily be equalized and made to act in harmony upon either side of said running stone by means of the adjustable driver (d, d') thereby preserving the proper equilibrium of the running stone and thereby greatly facilitating the process of grinding.

The driver (d, d') may be used with equal 45 advantage when the lower stone is, made the runner, instead of the upper, one, the balance rynd and upper portion of the shaft in such cases being dispensed with.

What I claim as my invention and desire 50 to secure by Letters Patent is—

The driver (d, d') constructed, and arranged, with reference to the shaft (C) and cap (e), substantially as and for the purposes set forth. 55

In testimony of which invention I have hereunto set my hand.

FERDINAND WALTERS.
